US0D1006558S

(12) **United States Design Patent** (10) **Patent No.:** **US D1,006,558 S**
(45) **Date of Patent:** **** Dec. 5, 2023**

(54) **FOOD SLICER**

(71) Applicant: **Williams-Sonoma, Inc.**, San Francisco, CA (US)

(72) Inventors: **Karl Edward Ludeman**, Oakland, CA (US); **Caleb Ferris**, Oakland, CA (US)

(73) Assignee: **Williams-Sonoma, Inc.**, San Francisco, CA (US)

(**) Term: **15 Years**

(21) Appl. No.: **29/785,861**

(22) Filed: **May 27, 2021**

(51) **LOC (14) Cl.** **07-04**

(52) **U.S. Cl.**

USPC **D7/673**

(58) **Field of Classification Search**

(57) **CLAIM**

The ornamental design for a food slicer, as shown and described.

DESCRIPTION

FIG. 1 is a perspective view of the food slicer;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view of the food slicer in an open state.

The broken lines showing portions of the article form no part of the claimed design.

1 Claim, 8 Drawing Sheets
